ELWOOD W. SACHSENMAIER AND ROBERT H. MOELLER, OF CHARLOTTE, NORTH CAROLINA, ASSIGNEES TO LARKWOOD SILK HOSIERY MILLS, INC., OF CHARLOTTE, NORTH CAROLINA, A CORPORATION OF DELAWARE

DESIGN FOR A STOCKING

Application filed December 7, 1931. Serial No. 41,997. Term of patent 14 years.

To all whom it may concern:

Be it known that we, ELWOOD W. SACHSEN-MAIER and ROBERT H. MOELLER, citizens of the United States and residents of Charlotte, in the county of Mecklenburg and State of North Carolina, have invented the new, original, and ornamental Design for a Stocking, of which the following is a specification.

Reference is had to the accompanying drawings, forming part thereof, wherein—

We claim:

The ornamental design for a stocking substantially as shown and described.

ELWOOD W. SACHSENMAIER.
ROBERT H. MOELLER.
